UNITED STATES PATENT OFFICE.

WILLIAM S. SEYMOUR, OF PHILADELPHIA, PENNSYLVANIA.

DESIGN FOR A PACKAGE-HOLDER.

SPECIFICATION forming part of Design No. 29,333, dated September 13, 1898.

Application filed August 19, 1898. Serial No. 689,021. Term of patent 7 years.

To all whom it may concern:

Be it known that I, WILLIAM S. SEYMOUR, a citizen of the United States, residing in Philadelphia, in the county of Philadelphia and State of Pennsylvania, have invented, designed, and produced a certain new and useful Design for a Package-Holder; and I do hereby declare the following to be a full, clear, and exact description of the invention, such as will enable others skilled in the art to which it appertains to make and use the same.

My invention relates to a certain new and original design for package-holders, and is illustrated in the accompanying drawings, wherein—

Figure 1 represents a perspective view of a package-holder embodying the design. Fig. 2 represents a top plan view thereof.

Similar letters of reference indicate similar parts in both views. 20

As shown in the drawings, the main body portion *a* of the package-holder is hollowed out longitudinally throughout its length, and the side portions *b* extend downwardly at an incline terminating in the reversely-curved hook-like bends *c*. 25

What I claim is—

The design for a package-holder, substantially as shown and described.

In testimony whereof I affix my signature 30 in presence of two witnesses.

WILLIAM S. SEYMOUR.

Witnesses:

F. B. WILLS, Jr.,
C. SPINDLER.
